UNITED STATES PATENT OFFICE.

THOMAS CORSCADEN, OF NEW BRITAIN, CONNECTICUT, ASSIGNOR TO THE AMERICAN PULLEY COMPANY, OF PHILADELPHIA, PENNSYLVANIA.

DESIGN FOR A PULLEY-SEGMENT.

SPECIFICATION forming part of Design No. 30,596, dated April 18, 1899.

Application filed May 8, 1897. Serial No. 635,746. Term of patent 14 years.

To all whom it may concern:

Be it known that I, THOMAS CORSCADEN, a citizen of the United States, residing at New Britain, in the county of Hartford and State 5 of Connecticut, have invented and produced a new and original Design for a Pulley-Rim Segment, of which the following is a specification, reference being had to the accompanying drawings, in which—

10 Figure 1 is a perspective view of my pulley-rim segment. Fig. 2 is a side elevation of the pulley-rim segment, and Fig. 3 is a transverse section of same.

The leading or material feature of my device 15 consists of the pulley-rim segment A, having a rolled or beaded edge B on one side and an inwardly-projecting flange 2 on its other side, the inner edge of said flange being concentric to the pulley-rim and terminating at a short

distance therefrom, as shown. At one end 20 of the roll or bead B is a dowel-pin 3 slightly projecting therefrom. The entire rim-segment forms one-half of the circumference of the wheel, and the flange 2 and face or body of the rim-segment A stand at about right angles to each other. 25

The plane-faced rim-segment, with the flat, thin, and inwardly-projecting flange 2 at one edge and roll B at the other, constitutes a very simple and pleasing design. 30

What I claim as new, and desire to secure by Letters Patent, is—

The design for a pulley-rim segment as herein shown and described.

THOMAS CORSCADEN.
